(57) **CLAIM**

The ornamental design for a notebook computer, as shown and described.

DESCRIPTION

FIG. 1 is a perspective view of a notebook computer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof shown in an alternate position;

FIG. 10 is another perspective view thereof shown in an alternate position;

FIG. 11 is a perspective view thereof shown in another alternate position; and,

FIG. 12 is a perspective view thereof showing the notebook computer in a closed status.

The even-dash broken lines illustrate portions of the notebook computer that form no part of the claimed design. The dot-dash broken lines define the bounds of the claimed design and form no part thereof.

1 Claim, 10 Drawing Sheets
